UNITED STATES PATENT OFFICE.

CHARLES F. KARR, OF WASHINGTON, DISTRICT OF COLUMBIA.

TOILET-COMB.

1,088,588.

Specification of Letters Patent.

Patented Feb. 24, 1914.

Application filed April 2, 1913. Serial No. 758,385.

To all whom it may concern:

Be it known that I, CHARLES F. KARR, a citizen of the United States, and a resident of Washington, in the District of Columbia, have invented certain new and useful Improvements in Toilet-Combs, of which the following is a full and clear specification, reference being had to the accompanying drawings, in which—

- 10 Figure 1 is a side elevation of a comb, a portion of whose teeth is constructed in accordance with my invention; Fig. 2 is an enlarged fragmentary front view of the comb whose teeth are constructed in accordance with my invention; Fig. 3 a section on the line 3—3 of Fig. 1; Fig. 4 a section on the line 4—4 of Fig. 2; Fig. 5 a view similar to Fig. 4 showing teeth having a different cross section; Fig. 6 a view similar to Fig. 3 20 showing a groove having a greater capacity than the one shown in Fig. 3; and Fig. 7 an enlarged face view of one of the teeth showing another form of scalp engaging edge.

The object of this invention is to so shape 25 the teeth that the comb may not only be used for combing the hair in the usual manner but also shall be capable of use as a scalp-cleaning implement, as more fully hereinafter set forth.

30 In the drawing I have illustrated my invention as applied to a comb of a well known type, having half of its teeth thicker and more widely spaced than the other half but it will be understood that the type of comb 35 is immaterial and that the invention may be applied to a comb whose teeth are uniform in size and spacing.

In the drawing I have shown only the larger teeth shaped according to my invention, but it will be clearly understood that it is within the spirit of my invention to use 40 all the teeth or any group or series thereof, as is obvious.

In accordance with my invention the 45 teeth are or may be of the usual size and shape except that in one face of each tooth a longitudinal depression or groove *a* is formed. This groove is preferably concave in cross-section and is sufficiently wide to

form edges *b* along each side of the tooth. 50 This groove extends from the free end of the tooth upwardly as far as may be desired; in the drawing I have shown them extending up about half the length of the tooth. The upper extremity of the groove 55 gradually decreases in depth until it merges into the face of the tooth, and at its other end the groove preferably terminates short of the extreme end of the tooth, thereby giving to the working-end of the tooth an approximately spoon-shape; the side edges *b* being thus continued around the end of the tooth. The reverse, or what may be termed the rear; face of the tooth is shaped as usual or in any approved manner. 65

In use, it will be seen that if the comb be drawn through the hair with its non-grooved tooth faces in front it will operate precisely in the manner as the ordinary comb, since neither the grooves nor the edges 70 formed thereby interfere in the least with the free passage of the teeth through the hair or cause any more friction on the scalp than comb teeth of the usual construction. When however the comb is moved through 75 the hair with the groove faces facing in the direction of movement and with the teeth in contact with the scalp, the spoon-shaped ends of the teeth will loosen the dandruff and dust and direct it into the grooves where 80 it will collect and adhere to the teeth. It will be understood that, as shown in the drawing, the scalp-engaging edges of the spoon-shaped portion as well as the edges of the grooved portion of the teeth are sufficiently dull or rounded to avoid any injury 85 either to the scalp or the hair. In actual use of my comb it has been found necessary to exert but an extremely gentle pressure on the scalp to cause the dandruff to be loosened 90 and collected into the grooves. To remove the collected dandruff it is simply necessary to tap the comb sharply or, if the collected matter be too oily for dislodgment in that manner, by simply running the fingers or a 95 piece of cloth down the faces of the grooves. This latter method of cleaning is facilitated by tapering or merging the upper ends of

the grooves into the faces of the teeth, as described and shown.

Having thus described my invention, what I claim as new, and desire to secure by Letters Patent, is—

A toilet comb having a series of its teeth each provided with a groove in one face which terminates in an approximately spoon-

shaped scalp-engaging edge at the lower end of the tooth, for the purpose set forth. 10

In testimony whereof I hereunto affix my signature in the presence of two witnesses.

CHARLES F. KARR.
